CLAIM

The ornamental design for a gondola for an airship, as shown and described.

DESCRIPTION

FIG. 1 is a left side elevational view of a gondola for an airship showing my new design;

FIG. 2 is a front elevational view thereof;

FIG. 3 is a reduced right, bottom perspective view thereof, and

FIG. 4 is a rear elevational view thereof.

The broken lines shown in FIGS. 1 through 4 are for illustrative purposes only and form no part of the claimed design.

FIG. 4.
